BABY TRAVEL CRADLE

Gerald Joseph Peltier, 834 E. Philadelphia,
Pomona, Calif. 91766

Filed Dec. 26, 1972, Ser. No. 318,019

Term of patent 14 years

Int. Cl. D6—01

U.S. Cl. D6—14

FIG. 1

FIG. 2

FIG. 3

FIG. 4

FIG. 5

FIG. 6

FIG. 1 is a perspective view of a baby travel cradle showing my new design;

FIG. 2 is a top plan view;

FIG. 3 is a left side elevational view;

FIG. 4 is a front elevational view;

FIG. 5 is a bottom plan view; and

FIG. 6 is a rear elevational view.

I claim:

The ornamental design for a baby travel cradle, substantially as shown.
